UNITED STATES PATENT OFFICE.

EDWARD G. BUDD, OF PHILADELPHIA, PENNSYLVANIA, ASSIGNOR TO HALE-KILBURN METAL COMPANY, OF PHILADELPHIA, PENNSYLVANIA, A CORPORATION OF PENNSYLVANIA.

FRAME CONSTRUCTION.

No. 918,959.

Specification of Letters Patent.

Patented April 20, 1909.

Application filed December 21, 1907. Serial No. 407,585.

To all whom it may concern:

Be it known that I, EDWARD G. BUDD, a citizen of the United States, residing in the city and county of Philadelphia, State of Pennsylvania, have invented a certain new and useful Improvement in Frame Construction, of which the following is a specification.

This invention is directed to the improvement of the construction of frames consisting of two or more hollow metallic frame-members secured together at their ends, and has reference, more particularly, to the method of making the joints between the ends of the members.

15 The invention is of particular utility in the construction of frames for metallic doors and in window frames and sashes consisting of frame-members of sheet-metal pressed to the form of hollow rails, the ends of these rails being secured together.

20 The object of the invention is to provide an improved and economic method of securing together the ends of the frame-members, making a uniform joint possessing great strength and producing a frame which is of attractive appearance.

25 In accordance with the invention, the ends of the frame-members are welded together so that they form a unitary structure, as in this way great strength is secured. A corner-box is employed underlying the joint between the frame-members and extending a short distance within the ends thereof. This box is preferably of such size that it fits 30 within the ends of the frame-members and completely fills the same. The use of a metallic corner-box for this purpose is open to the objection that it absorbs the heat rapidly and conducts it away from the welding point, making it difficult to raise the ends of the rails to the welding temperature quickly and without too great heating of the portions of the rails adjacent to the ends. I therefore employ a corner-piece of a material 35 which will not absorb heat or which will absorb it quite slowly. Such a corner-piece may be made of wood but as the welding flame is apt to burn the wood of the corner-piece, I associate with the latter a heat-resisting material arranged directly under the line of the weld. A strip of asbestos 40 may be employed for this purpose and this may be inlaid in the wooden corner-piece in position to underlie the line of the joint.

45 The preferred embodiment of my invention is illustrated in the accompanying drawings in which—

Figure 1 is an elevation of the lower portion of a metallic door, Fig. 2 is an enlarged view of one corner thereof, broken away and sectioned in part, and Fig. 3 is a section on line 3—3 of Fig. 1.

50 Referring to these drawings, the door shown consists of a frame formed of rails 1, 2 and 3 secured together at their ends and a panel 4 secured to these rails. Each of the rails is hollow, of rectangular cross-section and formed of pressed sheet-metal. Preferably a single strip of sheet-metal is employed in making one of the rails, this being 55 pressed to rectangular form to bring the lateral edges together and form a flange on the inner side of the rail to which the panel 4, consisting of one or more sheet-metal plates, is secured. The ends of the rails are preferably mitered, as shown in the drawings, 60 though this is in no way essential.

65 At each of the corners of the frame is a corner-piece 5 underlying the junction of the ends of the rails and extending a short 70 distance within the ends thereof. This piece is accurately cut to the interior dimensions of the rails so that it completely 75 fills the openings in the rails at the ends thereof. Corner-piece 5 is made of wood or 80 a similar material which will absorb and 85 conduct heat but slowly. In this corner-piece, grooves 6 are cut in such positions that they will directly underlie the joint between the two frame-members. Strips of 90 heat-resisting material 7, such as asbestos, are laid in these grooves, these strips being 95 of such size that they completely fill the grooves and present surfaces flush with those of the corner-piece.

95 With the parts thus constructed, the ends of two rails are brought together with a corner-piece lying within them, and the welding flame is applied to the edges to be joined. As wood and asbestos absorb and radiate 100 heat very slowly, the extreme ends of the rails will be quickly raised to the welding temperature and the asbestos being directly under the line of the weld protects the wooden corner-piece against being burned 105 by the flame. In order to hold the parts in proper relative positions, the rails may be clamped to the corner-piece during the welding operation, there being no danger of crushing the asbestos as it fits snugly in the 110

groove in the corner-piece. By joining the frame members in this way, a unitary structure is produced and one possessing great strength. The employment of a corner-box 5 which will not absorb heat and conduct it away from the line of the weld permits of much more rapid operation and by providing the heat-resisting strip directly under the weld, a corner-box of wood may be employed.

Having described my invention what I claim as new therein and desire to secure by Letters Patent of the United States is:

1. The combination of two hollow frame-members of pressed sheet-metal having their ends welded together to form a unitary structure and a corner-piece underlying the joint between said members and extending within the ends thereof, said corner-piece 20 having non-combustible material therein which will absorb heat but slowly, substantially as described.

2. The combination of two hollow frame-members of pressed sheet-metal having their 25 ends welded together to form a unitary structure, a cornerpiece of wood extending within and filling the ends of said members and heat-resisting material directly underlying the joint between said members, substantially as described.

3. The combination of two hollow frame-members of pressed sheet-metal having their 30 ends welded together to form a unitary structure, a corner-piece extending within the ends of said members formed of a material which will absorb heat but slowly, and heat-resisting material directly underlying the joint between said members.

4. The combination of two hollow frame- 40 members of pressed sheet-metal having their ends welded together to form a unitary structure, a corner-piece extending within the ends of said members having a groove therein, and heat-resisting material in said

groove underlying the joint between said 45 members, substantially as described.

5. The combination of two hollow frame-members of pressed sheet-metal having their ends welded together to form a unitary structure, a corner-piece extending within 50 the ends of said members and completely filling the same, said piece having a groove therein, and heat-resisting material in said groove underlying the joint between said members, substantially as described.

6. The combination of two hollow frame-members of pressed sheet-metal having their ends welded together to form a unitary structure, a corner-piece of wood extending within the ends of said members and completely filling the same, said piece having a groove 60 therein, and asbestos in said groove underlying the joint between said members, substantially as described.

7. The combination of two hollow frame-members of pressed sheet-metal having their ends welded together to form a unitary structure, a cornerpiece of wood extending within and filling the ends of said members, said piece having a groove therein, and heat- 70 resisting material in said groove underlying the joint between said members, substantially as described.

8. The combination of two hollow frame-members of pressed sheet-metal having their ends welded together to form a unitary structure, a cornerpiece extending within and filling the ends of said members, said piece having a groove therein, and asbestos in said groove underlying the joints between 80 said members, substantially as described.

This specification signed and witnessed this 17th day of December, 1907.

EDWARD G. BUDD
